(57) **CLAIM**

The ornamental design for a single-use temperature and humidity data logger as shown and described.

DESCRIPTION

The file of this patent contains at least one reproduction/photograph executed in color. Copies of this patent with color reproduction(s)/photograph(s) will be provided by the Office upon request and payment of the necessary fee.

FIG. 2.1 is a front view of the single-use temperature and humidity data logger embodying our design;

FIG. 2.2 is a back view thereof;

FIG. 2.3 is a left side view thereof;

FIG. 2.4 is a right side view thereof;

FIG. 2.5 is a top view thereof;

FIG. 2.6 is a bottom view thereof; and

FIG. 2.7 is right side perspective view thereof.
